UNITED STATES PATENT OFFICE.

ALOIS MIKLAS, OF VIENNA, AUSTRIA-HUNGARY, ASSIGNOR TO GEO. BORGFELDT & CO., OF NEW YORK, N. Y.

TOY.

SPECIFICATION forming part of Letters Patent No. 453,201, dated June 2, 1891,

Application filed February 25, 1891. Serial No. 382,736. (No model.)

To all whom it may concern:

Be it known that I, ALOIS MIKLAS, turner, a subject of the Emperor of Austria-Hungary, a citizen of the city of Vienna, residing 5 at Vienna, VI Wallgasse 17, have invented a new and useful Toy, of which the following is a specification.

My invention relates to a toy by which an optical illusion is produced; and it consists of 10 a frame-work supporting two rollers, upon which rollers in opposite directions is closely wound a long piece of cloth or the like, so arranged on both rollers that the general appearance of said rollers is that they are entirely disconnected, and that they are 15 revolved one by friction with the other when the latter is revolved by means of a small crank.

The object of my invention is to construct 20 a toy so that by introducing a slip of paper or the like in one side and by turning the proper roller the paper will appear to run through the wringer and come out on the opposite side printed, or vice versa.

25 My invention is illustrated by the accompanying drawings, in which—

Figure 1 is a front view of my device, showing a printed slip of paper partially wound upon one of the rollers. Fig. 2 is a rear view 30 of Fig. 1, showing a blank piece of paper being rolled out from between the rollers; and Fig. 3 is a cross-section of the rollers and slips of paper on the line 3 3, Fig. 2.

Similar letters refer to similar parts in all 35 figures.

A A is the frame-work supported by the post B on any suitable standard F.

D D' are two rollers hung in the frame A, one end of each being adapted to receive the 40 removable crank-handle a. Around each of these rollers is wound in opposite directions a strip of cloth E, long enough so that the space between said rollers is almost completely filled by the various thicknesses of 45 the cloth around the rollers. By introducing a strip of paper x between the rollers and turning one of the rollers (for instance D,

Fig. 1) by means of the removable crank a the printed scrap x of paper, as shown in Fig. 1, is wound in between the rollers, but, instead 50 of going through, is wound up on the roller D between the different layers of cloth E. By then introducing another scrap of paper y on the opposite side of the roller and by placing the crank a in the end b' of the other 55 roller D the said roller may be revolved so as to draw in this last scrap y of paper; but at the same time the paper x, previously introduced, will be unwound and ejected from the opposite side. 60

In operation, by introducing and concealing several printed slips x x of paper—such as checks or the like—into one side of the machine, one after another, the device is ready 65 for exhibition. These slips x x are concealed between the cloth E and one roller. By then taking a number of blank slips y y and rolling them one after another into the opposite side of the machine, as in Fig. 3, the printed slips x x, previously rolled upon the other 70 roller, simultaneously roll out from the opposite side, producing the very striking illusion of printing without the aid of type, &c. In other words, the toy is used to make believe 75 that the blank pieces of paper are printed and printed pieces made blank by the machine.

Having thus described my invention, what I desire to secure by Letters Patent and claim is—

The combination, in a toy, of the frame A and the rollers D D' with the cloth covering E, reversely wound on said rollers, and the removable crank a, adapted to turn either of the rollers, substantially as shown and described. 80 85

In testimony whereof I have signed this specification in the presence of two subscribing witnesses.

ALOIS MIKLAS.
